UNITED STATES PATENT OFFICE.

LLOYD W. DEDRICK, OF PUTNAM, NEW YORK.

AUTOMATIC WAGON-BRAKE.

1,182,992.

Specification of Letters Patent. Patented May 16, 1916.

Application filed November 29, 1913. Serial No. 803,811.

To all whom it may concern:

Be it known that I, LLOYD W. DEDRICK, a citizen of the United States, residing at Putnam, in the county of Washington and State of New York, have invented certain new and useful Improvements in Automatic Wagon-Brakes, of which the following is a specification.

This invention relates to automatic wagon brakes and more particularly to that type in which the brake shoes are automatically thrown into contact with the wagon or vehicle wheels by the "holding back" operation of the horses in descending a hill.

15 A principal object of this invention is to provide a device of this character in which the brake is immediately applied by the action of the horses, the brake shoes being of such a construction as to be thrown out of frictional engagement with the wheels when the wheels are traveling reversely for backing the vehicle or wagon.

Other objects as well as the nature, characteristic features and scope of my invention will be more readily understood from the following description taken in connection with the accompanying drawings and pointed out in the claim forming a part of this specification.

30 Referring to the drawings:—Figure 1 is a top plan view of a wagon brake constructed in accordance with my invention illustrating the application thereof; Fig. 2 is a longitudinal sectional view of the same; Fig. 3 is a detail enlarged sectional view of one of the brake shoes showing the manner in which the same is connected to the brake beam; Fig. 4 is a detail enlarged top plan view showing the manner in which one of the operating rods is connected with the actuating ferrule; and Fig. 5 is a longitudinal sectional view of the same.

In the drawings wherein is illustrated the preferred embodiment of this invention, an ordinary wagon 5 is provided which comprises front and rear axles 6 having wheels 7 mounted on the opposite ends thereof and provided with front and rear hounds 8 which are connected by a reach 9 in the ordinary manner. A tongue 10 is arranged in the front hound 8 in the usual manner and is secured thereto by a pin or bolt 11. The tongue is longitudinally recessed or slotted as indicated at 12 and shown to advantage in Fig. 2, and has a ferrule 13 slidably mounted thereon, which is in engage-

ment with a neck yoke, not shown in the drawings, in the usual manner.

Slidably mounted in the elongated recess 12 is an actuating rod 14 one end of which is curved to provide a hook 15 which is in engagement with the ferrule 13 adjacent the inner end of the latter as advantageously illustrated in Fig. 5, the opposite end of said rod being curved to provide a hook 16 which is in engagement with one end of a link 17, the opposite end of the latter being bifurcated and pivotally engaged with a second link 18. The link 18 is pivotally engaged with a lever 19, the latter being pivoted approximately midway its ends on the pin or bolt 11 and adapted to be rocked by the operation of the rod 14 to impart motion to a second actuating rod as indicated at 20, said actuating rod having the extreme rear end thereof engaged with a lever 21 identical with the lever 19, the lever 21 being pivotally engaged, at 22 to the reach 9 and having its upper end in engagement with a brace rod or yoke member 23, the latter having the opposite ends thereof detachably engaged with the brake beam 24.

Brake shoes 25 are detachably associated through the medium of bolts 26 and thumb nuts 27 to the opposite ends of the brake beam 24, each of the brake shoes having the upper ends thereof enlarged and the lower end tapering so as to provide an arcuate contacting face 28 whereby to prevent the frictional engagement of said face with the vehicle wheel when the wagon is being backed with a consequent reverse movement to the wheels.

Integrally formed on the link 17 and extending at a substantially right angle to the body thereof is an arm or lug 29 which may be used as a foot lever for facilitating the disengaging of the brake shoes 25 from engagement with the rear wheels 7 by merely exerting pressure thereon so as to cause the lever 19 to be actuated on its pivot 11. In order to retain the actuating rod 14 in the recess 12 a guard 30 is provided which in the present instance comprises a metallic strap the opposite ends of which are secured to the tongue 10 through the medium of rivets or any other suitable securing means.

In operation the neck yoke is engaged with the ferrule 13 in a suitable manner, the neck yoke in turn being in connection with the collars of the horses thereby causing pressure to be exerted on the ferrule 13

so as to actuate the same on the tongue 10 when descending a hill or the like thereby imparting movement to the rod 14 causing the same to be operated rearwardly and 5 causing power to be communicated to the rod 20 so as to throw the brake shoes 25 in engagement with the wheels 7 by the actuation of the mechanism heretofore pointed out. When it is desired to back the wagon, 10 it is seen that pressure will likewise be exerted on the ferrule 13 causing the same to be actuated rearwardly on the tongue 10 so as to impart movement to the rods 14 and 20 for actuating the shoes 25, but in view of 15 the peculiar formation of shoes as used in the present instance the shoes instead of being frictionally engaged with the outer periphery of the wheels 7 are sufficiently disengaged therefrom so as to prevent the locking 20 of the wheels for retarding the course of the vehicle.

It will be understood that the above description and accompanying drawings comprehend only the general and preferred embodiment of my invention and that various 25 minor changes in details of construction,

proportion and arrangement of the parts may be made within the scope of the appended claim and without sacrificing any of the advantages of my invention. 30

Having thus fully described my invention what I claim as new and desire to secure by Letters Patent is:—

A wagon brake including a rod extending longitudinally of the wagon tongue and 35 connected at one end to a ferrule slidably mounted on the tongue, the opposite end thereof bent to form a hook, a link having an aperture in one end to receive the hook and the opposite end yoked, a foot operating 40 means connected to the link, a second link pivotally connected to yoked end, of the first link, and itself having a yoked end and means associated with said second link for operating the brake beam. 45

In testimony whereof I affix my signature in presence of two witnesses.

LLOYD W. DEDRICK.
